UNITED STATES PATENT OFFICE.

ALVA HAYS CAVEN, OF YOUNGWOOD, PENNSYLVANIA.

TROLLEY-CONTACT.

1,138,279.

Specification of Letters Patent.

Patented May 4, 1915.

Application filed May 7, 1914. Serial No. 837,042.

To all whom it may concern:

Be it known that I, ALVA H. CAVEN, a citizen of the United States, residing at Youngwood, in the county of Westmoreland 5 and State of Pennsylvania, have invented a new and useful Trolley-Contact, of which the following is a specification.

The present invention relates to improvements in trolley contacts, one object of the 10 invention, being the provision of a novel contact, adapted to be connected to and supported from a trolley wire and constituting a means whereby current is diverted from the trolley wire through the wheel to signal controlling means, as are particularly set forth 15 in my co-pending application Serial No. 807,296 and my U. S. Letters Patent issued July 1, 1913, No. 1,066,380, one object of the present invention being the provision of a 20 construction, in which the wheel engaging contacts are properly supported and insulated from the protecting hood so as to prevent accidental arcing with the trolley wire and also whereby an overlapping contact 25 with the trolley wheel may be produced to operate the switch of the signal controlling solenoid as particularly set forth in my co-pending application filed even date herewith, 30 Serial No. 837,043.

With the foregoing and other objects in view which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

40 In the drawings Figure 1 is a bottom plan view of my complete contact. Fig. 2 is a section taken on line 2—2 of Fig. 1.

Referring to the drawings, the numeral 1 designates a trolley wire which is properly 45 supported from the plate 2 and is connected by the screw 3 to the block 4 of insulation. Connected to the block 4 and housing the same from above is a metal hood 5, which is open at both ends, the aprons 6—6' being 50 diverged downwardly to correspond with the opposite walls of the block 4, so that rain or snow may be properly drained therefrom. The screws 7 constitute a means for attaching the hood 5 to the block 4.

55 Attached to the inner face of the respec-

tive aprons 6—6' of the hood 5 are the strips 8 and 8' of insulation to each of which is attached a metal contact member 9 or 9'. These metal contact members 9 and 9' are attached at one end only as at 10, their free ends 11 being disposed for sliding movement through a strap 12 attached to the respective strips of insulation. As the contact strips 9 and 9' are upon each side of the trolley wire 1, the peculiar mounting thereof permits a slight 60 resiliency in each member to accommodate for varying sized trolley wheels, so that when a wheel engages the trolley 1 in passing below the hood 5, the sides of the wheel will engage the respective contact plates 9 and 9' and 65 thus shunt the current from the trolley to the plates 9 or 9' and to conductors led therefrom, there being a conductor led from each contact plate 9 or 9' to its respective controlling solenoids (not shown).

70 It will be noted in Fig. 1 that the contact plate 9 as viewed from the left is slightly in advance of the contact plate 9', thus insuring the engagement of the plate 9 when the trolley wheel is moving from left to right before the wheel engages the plate 9', thus the circuit controlled by the contact plate 9 will be energized and before the trolley wheel has disengaged the contact plate 9', the same will 75 engage the contact plate 9' and thus shunt the current or circuit to the plate 9' and the solenoid controlled thereby. The particular reason for this is clearly set forth in my co-pending application filed even date herewith, and in which the present detail structure is also illustrated. With this form of 80 trolley contact, and as in systems when trolley cars operate in one or both directions, a car entering the block and then backing from the same block will cause the signals to indicate such to cars in adjacent blocks.

85 What is claimed is:

A trolley switch, including a trolley wire supporting member, a block of insulation attached thereabove and supported thereby, a metal hood attached to the block of insulation and held in contact with the trolley carrying member by the block of insulation said metal hood being provided with two longitudinally disposed and depending parallel 100 aprons, two insulating strips of equal length, one strip attached to the inner face of each apron, said strips being disposed in overlapped relation and each extending from its 105 respective end of the hood to a point beyond 110

the center of the hood, and two resilient metal plates of equal length disposed one upon each side of and parallel to the trolley wire, the terminals of said plate being connected to their respective insulating strips and thereby from the hood, the inner ends of the contact plates being disposed in overlapped relation, whereby a trolley wheel will engage one of said contact plates and when 10 adjacent the central portion of the hood will

engage both contact plates to finally engage only the second contact plate.

In testimony that I claim the foregoing as my own, I have hereto affixed my signature in the presence of two witnesses.

ALVA HAYS CAVEN.
